METALLURGICAL APPARATUS

Jesse O. Betterton, Metuchen, and Carl Gall,
Woodbridge, N. J., assignors to American
Smelting and Refining Company, New York,
N. Y., a corporation of New Jersey

Application June 23, 1939, Serial No. 280,742

2 Claims. (Cl. 221—85)

The present invention relates to metallurgical apparatus, and more particularly to metallurgical pumps which are adapted to deliver molten metal, such as lead, for example, from a pool thereof to a refining environment for subjecting to refining reactions.

More specifically, the present invention relates to a pump which is adapted to be submerged in a pool of molten lead contained in a cast iron metallurgical kettle for delivering the lead to a chlorine reaction chamber, or other environment, in which the lead is refined.

In view of the fact that these metallurgical kettles are of different sizes, and may contain different depths of metal, it is desirable to provide a pump which is adapted for universal use with any size kettle or any depth of metal.

One of the objects of the present invention, therefore, is to provide a metallurgical pump which is adjustable to any desired depth of metal bath.

A further object of the invention is to provide a simple mechanism for effecting any desired vertical adjustment of the pump between wide limits.

Further objects and advantages of the present invention will become apparent as the description proceeds, and the features of novelty will be set forth in particularity in the appended claims.

The invention will be understood more readily from a consideration of the accompanying drawings, in which

Fig. 1 represents a plan view of the improved apparatus, showing the apparatus mounted on a metallurgical kettle.

Fig. 2 represents a sectional elevation of the apparatus taken on the line 2—2 of Fig. 1.

Fig. 3 represents an enlarged fragmentary sectional elevation of the lower portion of the supporting mechanism of the pump.

Fig. 4 is a sectional plan view of the pump-adjusting mechanism, taken on the line 4—4 of Fig. 3.

Fig. 5 is a side elevation of the upper portion of the apparatus, showing details of the adjusting means for the pump and mounting of the carrying means by which the apparatus may be transported between operative and inoperative stations, parts of the frame being shown in section.

Fig. 6 is a sectional elevation, taken on the line 6—6 of Fig. 5, looking in the direction of the arrows.

Fig. 7 is a sectional plan view taken on the

line 7—7 of Fig. 6, looking in the direction of the arrows, the view showing enlarged details.

Fig. 8 is a sectional plan view of a fragment of the supporting frame and guide member, the view being taken on the line 8—8 of Fig. 5, looking in the direction of the arrows.

Fig. 9 is a fragmentary plan view of the pump supporting section of the platform upon which the pump structure is carried.

Referring more particularly to the drawings, a metallurgical kettle is indicated at A, which is spanned by a platform B on which is mounted the adjustable pump C of the present invention, together with its adjusting mechanism.

The platform comprises suitable longitudinal I-beams and transverse channel members, suitably secured together, which support plates D which form the floor of the platform, and divide the floor into sections.

Suitable upright and horizontal angle members along the sides of the platform form hand- and guard-rails, such structure being indicated generally at E.

The pump construction is mounted on the platform at one of the floor sections, which may be disposed preferably over the deepest part of the kettle.

For this purpose, transverse channel members, such as those indicated at 10 and 12, are supplemented by additional channel members 14 and 16, these channel members being secured to the lateral I-beams 18 and 20 in any suitable manner, as by angle plates indicated at 22, which plates are riveted or welded in position, thereby forming a very rigid reinforced supporting structure for the pump mechanism. Obviously the members of this frame may be welded together directly, either with or without the angle plates.

40 A plate 24 is riveted to the bottom of this resulting structure, this plate having a relatively large hole 26 therein for ready reception of the pump shaft and housing therefor. The floor plate of this particular platform section is omitted.

At each corner of this supporting structure there is provided a vertical angle bar 28, and to the upper end of each pair of these bars there is secured horizontal angle bars 30, 32 extending longitudinally of the platform structure, the angle bars 30, 32 being reinforced by riveting to the upstanding webs 34, 36 of the top angle bars 38, 40 of the platform frame and which form the hand-rails of the platform.

The horizontal angle-bars 30, 32 are cut-away

as is indicated at 42, 44 to form recesses for receiving vertical guide bars 46, 48, which in turn, are secured by countersunk bolts 51 to plates 50, 52, which are shaped similar to each other. These plates 50, 52 are attached to the lifting bale 54, by which means the pump structure may be lifted and transported to other stations.

The junction between the bale 54 and the plates 50, 52 is effected by providing the ends of the bale with bifurcations, as are indicated by 56, 58 and passing bolts 60 and 62 through registering holes in the bale ends and the plates.

Positioned on the channel members 10 and 14 and suitably secured thereto is a boss 64, which is provided with a hole 66 extending through it, and it will be observed that the channel members 10 and 14 are spaced apart a distance which corresponds approximately to the diameter of the hole 66, so that an adjusting screw 68 may 20 pass freely therethrough.

This construction is repeated on the opposite side of the supporting frame with respect to the boss 70 and the spacing of the channels 12 and 16, a second adjusting screw 72 being received therein through the hole 74 in the boss 70.

It will be seen from the drawings that the upper portion of the holes 66 and 74 are enlarged to receive bushings 76 and 78, which are secured in position by pins 80 and 82, and which are 30 threaded internally to correspond to the threads 69, 71 of the screws 68, 72, these threads being shown as being right-hand threads.

From the drawings, it will be noted that each of these adjusting screws 68, 72 comprises a single screw shaft, which is formed into upper and lower section 73 and 110 by the right hand threads 69, 71 and by the left hand threads 112, a portion 94 of the shafts intermediate the threaded portion being provided with a sliding keyway 92 for securing the pinions 84, 86 to the respective shafts for rotating the same, these pinions being positioned in similar split housings 88, 90, the sections of which are shown as being bolted together, as is indicated at 98, 98, and 100, 100.

A casting 102 is provided to carry the pump housing. This casting will be referred to in greater detail hereinafter, but it will be noted at this point that it is provided with oppositely disposed flanges 104, 104, each of which has a hole therethrough, provided with an internally threaded liner 106, 106, which is held in place by dowel pins 108, and which receives the left-hand threads 112, 112 of the upper threaded portion 110, 110 of the adjusting screws.

It will be noted that the threads 112, 112 are left hand threads, whereas the threads 69, 71 are right hand threads, this arrangement providing double the amount of movement of the pump for each turn of the pinions 84, 86, than would be obtainable were all of the threads running in the same direction. The threads are all of equal pitch, on both screws. The pinions 84, 86 and the corresponding shafts 68, 72 are maintained in proper relative position by snap rings 111, 111, carried on collars 113, 113 provided in the screw shafts 68, 72.

The pinions 84, 86 are rotated by worm pinions 114, 114, which are of the same pitch, and which are enclosed in housings 116, 116, which housings are, as shown extensions of the gear housings 88, 90, there being one of the pinions 114 for each of the pinions 84, 86. A shaft 118 interconnects the pinions 114 so as to cause simultaneous and equal rotation thereof, each end of the shaft 118 being 70 75

provided with means 120, 120 for receiving an operating crank for enabling the shaft 118 to be turned, thereby rotating the pinions 114, 114, pinions 84, 86, and thence the screws, so that 5 rotation of the latter adjusts the entire casting 102 and the elements mounted thereon, as will be described in more detail below.

This casting comprises a plurality of webs 121, which connect the upper annular 122 part of the casting, which forms a seat for the operating motor 124, to the lower collar 126. This collar 126 has a hole through it to receive the operating shaft 128 for the pump 129. A second collar 130 is secured to the underside of collar 126, by 15 suitable securing means such as cap screws 132, 132, the housing 134 for the pump shaft 128 being welded to this collar as is indicated at 136. The cap screws 132 are accessible through openings 133 in the shaft housing 134.

The collar 126 of the casting 102 is provided with an internal upstanding annular boss 138, which has secured to it a top collar 140, which, with the boss 138, forms the seat for a thrust bearing 142.

A bushing 144 enclosing the pump shaft 128 also is secured to the casting collar 126, forming a lining for the hole through this collar 126 and defining a bearing for the shaft 128. A ring 146, fitting on the end of the bearing 144, which is tapered, seats the inner ball race of the bearing 142, a seal 148 being provided to prevent ingress of dirt around the bearing. The seal 148 is held in position by the weight of a flexible chain coupling which includes bearing blocks 150 and 152, which are secured together by a flexible chain 154.

The motor 124 is supported laterally by the spring pressure exerted by the plates 50, 52. These plates are bolted to the outer annular rim 156 of casting 102, thereby forming a unitary lifting structure, the back of the plates being secured to the guide bars 146, 148, thereby guiding the pump for operation.

It will be noted from Fig. 6 that the pump shaft 128 is secured through a screw 151 to the lower block 150 of the flexible chain coupling, the upper block 152 of which coupling is keyed, as is indicated at 153 to a shaft section 155. This section 155 is keyed, as shown at 157 to a ribbed compression coupling 158 held in place by bolts 160, and which is keyed, as indicated at 161, to the motor shaft 163.

Also, it will be noted from Fig. 7 that the worm shaft 118 is supported by bearing 162, 162, located 55 in the pinion housings 88, 90, the shaft 118 being secured to the worm pinions 114 by means of suitable keys, such as that shown at 164 in Fig. 4.

What is claimed is:

1. Metallurgical apparatus comprising, in combination, a supporting frame adapted to span a metallurgical container adapted to contain a pool of molten metal, the supporting frame comprising longitudinal and transverse supporting beams, a plate mounted on the beams, the said plate having a relatively large opening therein, a carrying frame mounted on the supporting frame and extending into the said opening, the carrying frame defining a mounting for a driving motor, a driving motor on the said mounting, a driven shaft adapted to extend into the said container, a pump on the said shaft, the said pump being adapted to be submerged in the said pool of molten metal, adjusting screws for vertically moving the said carrying frame, each of the said screws having oppositely running threads with an

intermediate unthreaded portion, means on the carrying frame and on the supporting frame for mounting and guiding the screws, the said means being threaded internally to correspond with the threads of the screws, operating instrumentalities for the screws connected thereto at their unthreaded portion and adapted to adjust the screws entirely equally, and means for actuating the said operating instrumentalities to turn the said screws simultaneously and equally for effecting an invariably straight movement of the carrying frame and pump and enabling vertical adjustment of the pump into any one of a multiple of positions relative to the said container.

2. Metallurgical apparatus comprising the 15 combination with a metallurgical container adapted to contain a pool of molten metal, of a pump adapted to be immersed in the said pool for

delivering molten metal therefrom to a remote station, mounting means on the container for mounting the pump, the said mounting means comprising a supporting frame and a carrying frame mounted on the supporting frame and movable therewith, the said carrying frame including a mounting for a driving motor, a driving motor on the said mounting, a shaft driven by the said motor, a pump on the shaft and operated thereby, screw devices for adjusting the carrying frame and pump to any desired depth relative to the said container, the said devices preventing lateral movement of the carrying frame and pump during adjustment thereof, and mechanism for simultaneously and equally operating the said screw devices.

JESSE O. BETTERTON.

CARL GALL.
